Application December 12, 1941, Serial No. 422,758

10 Claims. (Cl. 177—311)

This invention relates to systems for feeding aggregate materials such as coal, coke or the like and more particularly to an alarm device for such systems which will give an alarm if a stoppage occurs and thus aid in preventing interruptions in the feeding of aggregate materials through such systems.

The problem which this invention is designed to solve arises particularly in connection with the systems used to feed coal or coke to the fires under the boilers of a power plant. In such installations, coal or coke is commonly fed from an overhead bunker, through a weighing device, to a pulverizer-feeder or stoker of a power plant. If a stoppage occurs at any place in this system, the boiler ceases to be supplied with coal and it is highly desirable that this dangerous condition be remedied at the earliest possible moment. In present practice, wet, fine coal must often be burned under boilers and this wet, fine coal occasionally refuses to flow properly and causes stoppages in the system which quickly become dangerous if not corrected.

Numerous alarm devices have been proposed in the past but none have been positive or sure enough in their operation. Many such devices are readily clogged by coal and hence fail in operation and others are capable only of locating stoppages in certain relatively small sections of the system.

Accordingly, the present invention comprises a mechanism that operates in conjunction with the usual elements of a coal supply system in such a manner that the alarm device itself need not be exposed to the coal at all and yet will give a quick, dependable and accurate indication of whether or not coal is flowing in the system, and if not, where the stoppage has occurred.

Most coal feed systems consist of a bunker from which coal passes to a weighing mechanism and either a pulverizer-feeder or a stoker to which the coal passes from the weighing mechanism. One such weighing mechanism is described and illustrated in an application for Letters Patent of the United States filed by Arthur J. Stock on August 26, 1940, and assigned the Serial Number of 354,148. The alarm system of the present invention is particularly well adapted for use with this weighing device and hence will be described as it is used therewith. However, it is to be understood that the alarm device of the present invention may be used with any other similar weighing device.

It so happens that in the weighing mechanism of the aforementioned application, coal passes

from the bunker onto a belt conveyor which feeds it to a weighing hopper carried on scales. From this hopper the coal is discharged into a chute which directs it to a pulverizer-feeder or stoker. The operation of the belt conveyor is controlled by the scales which carry the weighing hopper so that the belt conveyor continues to operate until the weighing hopper balances the scales, at which time the belt conveyor stops until the weighing hopper has discharged and is ready to receive another load of coal.

The present invention preferably comprises two units, one operated by the belt conveyor and weighing mechanism, and the other operated by the stoker or pulverizer-feeder and weighing mechanism. Each unit consists of a driven means, driven in one case by the belt conveyor and in the other case by the pulverizer-feeder or stoker, and a re-setting device, operated, in either case, by the weighing mechanism. Each unit also includes a relay or switch mechanism which is operated by the driven means after it has been driven to a predetermined extent, providing it has not sooner been reset by the action of the weighing mechanism.

Thus, as the belt conveyor operates, or as the stoker mechanism or pulverizer-feeder operates, it drives the driven means toward a point where it will operate the relay or switch mechanism. However, if coal or other material is flowing through the system in a normal manner, the weighing mechanism will operate before the driven means reaches a point where it will actuate the relay or switch mechanism and the operation of the weighing mechanism will actuate the re-set device which will re-start the cycle. This continues as long as the system is in normal operation, but if for any reason coal ceases to flow in the system, the driven means will then be operated to a point where it will actuate the switch or relay mechanism, which in turn will operate an indicator or signal, thus informing the operator of the stoppage of the system.

If the stoppage occurs above the weighing hopper, the belt conveyor will operate for a longer period than usual in an attempt to supply a load of coal to the weighing hopper and this fact will cause operation of the signal of the alarm unit driven by the belt conveyor. On the other hand, if the coal stoppage occurs between the weighing hopper and the pulverizer-feeder or stoker, then the coal will pile up in the chute under the weighing hopper and prevent operation of the weighing mechanism, thus causing the pulverizer-feeder or stoker to operate for an unusually long period

between operations of the weighing mechanism, which fact will be indicated by the alarm unit driven by the pulverizer-feeder or stoker.

However, if the coal stoppage occurs above the weighing mechanism coal will soon cease to be delivered from the weighing mechanism to the pulverizer-feeder or stoker and hence the alarm covering this part of the system will also operate. To prevent this, a second mercury switch may be positioned alongside of the first in the upper alarm, and arranged so that upon actuation of the alarm this second switch will break the circuit of the lower alarm, thus preventing its operation. The lower alarm can then be set to have a slightly longer period before it operates, so that in case of a stoppage above the coal weighing mechanism the upper alarm will have a chance to render the lower alarm inoperative before it operates at all. However, even though the lower alarm does operate simultaneously with or a little before the upper alarm, it will be cut off by the operation of the upper alarm.

If the stoppage occurs between the pulverizer-feeder or stoker and the weighing mechanism, coal will pile up under the weighing mechanism and prevent the closing of the gate at the bottom of the hopper. Thus, the belt conveyor will be stopped before the upper alarm is operated but will simply remain in that state until the lower alarm has operated, the stoppage cleared and the system again in proper operation.

It will be apparent that either of the two alarm units may be used separately from the other, and that alarm units embodying the principles of this invention may be used in connection with systems employing other weighing devices of this same general character.

An understanding of the more detailed features of this invention and of its numerous advantages may be had by a study of the appended drawings and the following detailed description thereof.

In the drawings:

Figure 1 is a semi-diagrammatic illustration in side elevation, and with certain parts cut away to show the mechanism more clearly, of the principles of this invention applied to a coal supply system.

Figure 2 is a front elevation partly in section of one of the units employed according to this invention, the cover having been removed to expose the working parts.

Figure 3 is an end elevation of the same unit, showing the covering of the unit in place but sectioned to expose the interior parts.

Figure 4 is a wiring diagram showing the controls for the motor associated with the weighing mechanism; and

Figure 5 is a wiring diagram showing the manner in which the alarm units are connected for operation.

As illustrated in Figure 1, coal, coke or other aggregate material passes from bunker 11 into an automatic weighing device 12 of the type described in the above-mentioned application of Arthur J. Stock, and from this weighing device into a chute 13 which conveys it to a pulverizer-feeder 14. From this feeder it passes through a chute 15 into the furnace.

The automatic weighing device 12 will not be described here in detail since it is already the subject matter of another patent application, but it may be stated generally that it comprises a belt conveyor 16 driven by an electrical motor 17 so as to feed coal or the like from the bunker 11 into a weighing hopper 18 supported on scale beams 19.

and arranged to discharge through a gate 20 at the bottom thereof. The automatic weighing device is operated electrically in such a way that the electric motor 17 operates the belt conveyor 16 until such time as the weighing hopper 18 is filled to a point where it balances the beams 19 of the scales of the weighing mechanism, at which time current to the electrical motor 17 is interrupted so that the motor stops; the gate 20 is released so that it opens and allows the coal to discharge therefrom; the gate 20 then closes, the motor 17 is again energized and the cycle is repeated.

Upon reference to Figure 4 it will be seen that motor 17, which, as illustrated, is of the three phase type, is supplied with current through lines 55, 56 and 57 which lead into and through switch box 58. Within switch box 58 is a motor switch 59 operated by a solenoid 60. Conductors 61, 62, 63 and 64, as well as manual master switch 65 and mercury switches 66 and 67 control the flow of current to solenoid 60. Thus, when motor 17 is to be started to drive conveyor 16 so that aggregate material may be fed from bunker 11 to hopper 18, manual switch 65 is moved to closed position. This will close the circuit to solenoid 60 if switches 66 and 67 are also closed which will be the case if the hopper gate 20 is closed and the beam 19 is in horizontal position as is the case when hopper 18 is empty. As is more fully described in application Serial Number 354,148, filed August 26, 1940 and hereinbefore mentioned, mercury switch 67 is mounted in such a way that it is normally biased to circuit opening position but is held in circuit closing position by beams 19 when they are horizontal. When the hopper 18 fills, however, and the left end of beams 19, as viewed in Figure 1, rises, the normal bias of switch 67 will be effective and the circuit containing it will be opened. This will cause solenoid 60 to be deenergized and motor 17 to stop.

Upon reference to Figure 1 it will be seen that hopper gate 20 is held closed by a latch 68 which, by means not shown, is held in latching position by solenoid 69. Since, as can be seen in Figure 4, solenoid 69 is controlled by switch 59, it is evident that when mercury switch 67 opens upon tilting of beams 19, the deenergization of solenoid 60 and the opening of switch 59 will result in the release of latch 68 as well as the stopping of motor 17. Thus the hopper gate 20 will open under the influence of the weight of the material contained therein. The opening of gate 20 will also cause switch 66, pivotally mounted at 69a, to open so that the motor circuit may not be reestablished in the event a stoppage exists below gate 20 so that the quantity of aggregate under gate 20 is such as to impede its normal closing by counterweight action. In the absence of impediment gate 20 will close after discharging and so mercury switch 66 will be biased to circuit closing position. Similarly, the loss of the weight formerly in hopper 18 will cause beams 19 to return to horizontal position and so bias switch 67 to closed position. Under these conditions the circuit to motor 17 will be made as well as that to latch solenoid 69 and resetting solenoids 43 and 43a to be hereinafter more fully described.

The upper alarm unit which is shown in greater detail in Figures 2 and 3 is connected so that its driven means is driven by the motor 17 that drives the belt conveyor 16 and its reset mechanism is operated from the electrical circuit that operates the motor 17 in such a manner that the unit is re-set each time the motor is started, see Figure 5. The lower alarm unit 22 is connected

to be driven from the pulverizer-feeder 14 but is re-set in the same manner as is the upper unit 21 by the starting of motor 17. Thus, in the event that either the belt conveyor or the pulverizer-feeder operates for too long a period before the scales operate, complete their operation and re-start the motor 17, one or the other or both of the alarm units will cause a signal to be given.

The motor for or manner of operating pulverizer feeder 14 has not been shown since any conventional arrangement may be used. It will be understood, however, that in a normal installation pulverizer feeder 14 will operate continuously and entirely independently of motor 17 or the conveyor driven thereby.

Each of the alarm units specifically comprises, as shown in Figures 2 and 3, a frame or base 23 upon which are mounted the operating parts of the unit, and which is covered by a cover 24 fastened thereto in any suitable way as for example by machine screws 25 which pass into upstanding lugs on the frame.

The units may be attached to the frame of the weighing mechanism or to the frame of the pulverizer-feeder or stoker by appropriate bolts 26. Each unit is driven by a shaft 27 which extends from the mechanism from which the unit is to be driven into the unit itself and carries within the unit a worm 28. The shaft is connected to any appropriate driven shaft in the device from which it is driven, for example in the weighing mechanism to one of the shafts in the gearing between the electrical motor 17 and the belt conveyor 16, and in the pulverizer-feeder 14 to the main-drive shaft.

In each alarm unit there is a worm-wheel 29, which meshes with the worm 28 except during operation of the resetting device. The worm wheel is carried rotatably on a pivoted shaft 30, pivoted at a point 31, which is remote from the worm-wheel, in a sub-frame 32, which is attached to the main frame 23, by a pair of bolts 33. The weight of the pivoted shaft and the parts carried by it is partially counterbalanced by the action of a coil spring 34 connected between it and the sub-frame.

Mounted upon the pivoted shaft is a small hinged frame 35, which carries a mercury switch 36 and is so constructed that the mercury switch will normally remain in the "off" position. The hinged frame, however, carries an upstanding arm 37 which passes close to one of the faces of the worm-wheel 29 and the worm-wheel 29 has a projecting pin 38 upon that face so arranged that if the worm-wheel 29 is revolved to a sufficient extent, the projecting pin 38 will engage the upstanding arm 37 on the hinged frame and tilt the movable part of the hinged frame, which in turn tilts the mercury switch 36 so as to actuate it. The terminals of the switch are connected by a pair of leads 39 to a terminal block 40 mounted upon the sub-frame.

The teeth are removed from a part of the worm wheel 29, at the section indicated as 29a, so that once the worm wheel has revolved to a sufficient extent so that the projecting pin 38 engages the upstanding arm 37 on the hinged frame and tilts the movable part and with it the mercury switch 36, the worm wheel 29 will then reach a position where the part 29a from which the teeth have been stripped, will be opposite the worm 28, so that no further movement will take place. This effectually prevents the continued rotation of the worm wheel 29, which would

otherwise continue to rotate and break the switch mechanism.

The resetting mechanism consists of an arm 41 attached to the end of pivoted shaft 30, remote from the pivot 31, a dash-pot assembly 42 connected to the end of the arm 41 and a solenoid 43 which operates through the dash-pot to lift the pivoted arm 30, thus disengaging the worm-wheel 29 from the worm 28. The worm-wheel 29 is then caused to rotate back to its original position by a coil spring 44 which is connected between the arm 41 which is fixed to the end of the pivoted shaft 30 and the worm-wheel 29, in such a manner as to rotate the worm-wheel back to starting position.

In its starting position the pin 38 contacts a slider 45 which is carried on an upstanding lug 46 on the main frame 23 and held in position by thumb screw 47. The position of this slider may be adjusted to adjust the starting position of the worm-wheel.

There is also a second projecting pin 48 on the other side of worm-wheel 29, which projecting pin is positioned at an approximately 90° angle around the worm-wheel from the first pin. There is further, a second upstanding lug 49 on the main frame, on the other side of the worm-wheel from the lug 46, and the slider 45 may be transferred to this lug so as to cooperate instead with the second pin on the worm-wheel, thus making possible another range of starting positions for the worm-wheel.

The main body of the dash-pot arrangement 42 is connected directly to the arm 41 of the pivoted shaft 30 and the plunger 50 is connected to the armature 51 of the solenoid 43. Solenoid 43 is connected to conductors 56 and 57 leading to motor 17 so that solenoid 43 is energized only when the circuit to motor 17 is closed. The plunger 50 consists of the usual type of plunger element except that openings 52 are made through the plunger and a washer 53 placed around the shaft of the plunger and laid on top of the openings 52. Thus when the plunger moves upward, the openings 52 are closed by the washer so that the upward movement of the solenoid armature lifts the whole assembly and with it the end of the pivoted shaft and the worm-wheel 29. The dash-pot, shaft and gear thereafter return slowly to their original positions as leakage past the plunger takes place. However, upon release of the armature 51 of the solenoid, when the circuit to motor 17 is broken, the plunger 50 drops relatively quickly into place at the bottom of the dash-pot, since the washer 53 is lifted off the openings 52 by the upward pressure of the liquid below. The dash-pot may be filled with oil or any other desirable fluid.

The solenoid 43 is connected for operation to the terminal block 40 by leads 54. In operation, the leads from the mercury switch 36 are connected to an indicating or signalling device, shaft 27 is driven either from the mechanism which drives the belt conveyor or the mechanism which drives the pulverizer-feeder, or stoker and the solenoid is actuated from the motor circuit of the motor which drives the belt-conveyer. Thus, the worm-wheel starts in a position in which the pin 38 or 48 is against the slider 45, and rotates until the weighing device operates and stops the driving motor for the conveyor, and with it the shaft 27. At this time the current stops in the motor circuit, the solenoid 43 releases the armature 51 and the plunger 50 drops to the bottom of the dash-pot 42. Now, if the weighing device or weighing mechanism discharges the hopper full

of material, the hopper gate closes and the motor driving the belt-conveyer is again started. At the time of starting, the solenoid 43 is energized, the armature 51 is lifted, and this lifts the dash-pot assembly 42 and with it the end of the pivoted shaft 30, so that the worm-wheel 29 is lifted out of mesh with the worm 28. Spring 44 then revolves the worm-wheel 29 until the pin 38 or 48 strikes the slider 45. As the fluid leaks past the plunger in the dash-pot, the worm-wheel 29 is lowered into contact with the worm 28, and the cycle begins again.

If, for any reason, there is a stoppage of material above the belt-conveyer, then the conveyer will operate for an abnormally great number of turns before the weighing mechanism will operate. Therefore, the worm-wheel 29 will be turned further than normal and will strike the upstanding arm on the hinged frame 35, tilting the switch 36 and causing whatever indicator is used to be operated.

The details of operation of the signalling devices can be seen perhaps even more clearly from Figure 5 in which is shown a circuit diagram of the device. From the circuit between the starter switch 59 in box 58 and the motor, power is taken directly to operate in parallel both of the resetting solenoids 43 and 43a of the upper or scale alarm, and the lower or stoker or pulverizer-feeder alarm, respectively. Signal current is brought through leads 10 to the upper alarm device where it is connected in series to the mercury switch 36 to the indicating or signalling device 71. This signalling device may be an electric lamp, an electric horn, a relay, an electrically operated whistle, or any other device that will emit or display the desired signal upon actuation. In the lower or pulverizer-feeder alarm the connections are exactly the same. The signal current is brought through a pair of leads 12 connected in series with the mercury switch 36a and the signalling device 71a of the alarm.

From the foregoing it can be seen that if a stoppage occurs in or above bunker 11, belt 16 will operate without feeding coal to hopper 18. Thus, the number of turns of motor 17 will greatly exceed the normal number of turns necessary to supply a predetermined weight of aggregate to hopper 18. Motor 17 will continue to run because the circuit thereto is broken only by the tilting of beams 19 which will not occur unless the aggregate is actually reaching hopper 18. The effect of this will be to continue to drive gear 29 until the pin thereon strikes lever 31 and operates mercury switch 36 to give an alarm. If, on the other hand, a stoppage were to occur in chute 13, the aggregate would pile up so that gate 20 of hopper 18, after a discharge operation, could not close. Thus, although the circuit to motor 17 had been broken by the tilting of beams 19 before an alarm had been given, the failure of gate 18 to close prevents the reestablishment of the circuit to motor 17 which in turn prevents establishment of a circuit to either of solenoids 43 or 43a. As a consequence, the continued rotation on the part of pulverizer-feeder 14 will result in the operation of signalling device 71a to indicate a stoppage between hopper 18 and pulverizer-feeder 14.

When it is desired to render the stoker or pulverizer-feeder alarm inactive upon actuation of the upper or scale alarm it is only necessary to place a second mercury switch upon the tiltable frame 35 of the upper alarm and connect this mercury switch which is shown at 73 in dotted lines in Figure 5, in series with the mercury switch 71

36a of the lower alarm. The switch 73, however, is turned backwards in the hinged frame 35 so that contact is broken when the switch is tilted and made when the switch is in normal position. Thus the lower alarm unit can operate only if the upper alarm unit has not operated, because the operation of the upper alarm unit will break the indicating circuit of the lower alarm.

What is claimed is:

1. Apparatus for detecting stoppages in the flow of bulk material through a feeder system, which includes a driven feeding device having a rotating part and a batch delivery device receiving material from said feeding device, that comprises means driven by the rotating part of the feeding device to actuate an alarm signal after a predetermined angular displacement of the rotating part which is greater than the normal angular displacement incident to supplying a batch of bulk material to the delivery device, and means operated by said delivery device, upon the delivery of a batch, to reset the means driven by the rotating part of the feeding device and thus, in normal operation prevent the actuation of the alarm.

2. Apparatus for detecting stoppages in the flow of bulk material through a feeder system, including a driven feeding device having a rotating part and a batch weighing device receiving material from the said feeding device and periodically discharging the same, that comprises means driven by the rotating part of the feeding device to actuate an alarm signal after a predetermined angular displacement of said rotating part which is greater than the normal angular displacement incident to feeding sufficient bulk material to cause a discharge on the part of the weighing device, and means operated by said weighing device in the discharge cycle of its operation, to interrupt the operation of the means driven by the rotating part of said feeding device and to reset the same so as to prevent actuation of the alarm in normal operation.

3. Apparatus for detecting stoppages in the flow of bulk material through a feeder system, which includes a driven feeding device having a rotating part and a batch delivery device receiving material from said feeding device, that comprises an alarm device, an electric circuit controlling operation of said alarm device, a switch in said circuit, means driven by the rotating part of the feeding device to close said switch after a predetermined angular displacement of said rotating part greater than the normal angular displacement incident to supplying a batch of bulk material to the delivery device, and means operated by said delivery device upon the delivery of a batch of bulk material to reset the means driven by the rotating part and thus in normal operation prevent the closing of the switch in the alarm circuit.

4. Apparatus for detecting stoppages in the flow of bulk material through a feeder system, which includes a driven feeding device having a rotating part and a batch delivery device receiving material from said feeding device, that comprises a wheel driven by the rotating part of said feeding device; a pin on said wheel; an electrical switch, means connected to said switch and adapted to be contacted by said pin upon the rotation of said wheel to a predetermined extent so as to bias said switch to a circuit-closing position, an electric circuit controlled by said switch, an alarm device in said circuit, and means operated by said delivery device upon the delivery of a

batch of bulk material to reset said wheel to its starting position so as to prevent the closing of the electrical circuit controlling the alarm device unless the angular displacement of the rotating part of the feeding device is in excess of the angular displacement normal incident to supplying a batch to the delivery device.

5. Apparatus for detecting stoppages in the flow of bulk material through a feeder system which includes a driven feeding device having a rotating part, and a batch delivery device receiving material from said feeding device, that comprises; a worm, means for driving said worm from the rotating part of said feeding device, a worm wheel in mesh with said worm, a pin projecting from the face of said worm wheel, a normal, open switch in the path of said pin adapted to be closed when the latter strikes it, means normally biasing said pin to a starting position remote from the point of contact with said switch, an alarm device, an electric circuit including said switch and said alarm device, means operated by said delivery device upon the delivery of a batch of bulk material for disengaging said worm and worm wheel so that the latter will return to starting position, thus in normal operation preventing actuation of the alarm while if the angular displacement of the rotating part of the feeding device is greater than that normally required in feeding a batch of bulk material to the delivery device the worm and worm wheel will remain engaged and the pin on the latter will be caused to contact the switch and close the alarm containing circuit.

6. Apparatus as described in claim 5 in which the means for disengaging the worm and worm wheel is a dash-pot acting on the latter, the plunger of said dash-pot containing a check valve arranged so that the operation of the solenoid is immediately effective in disengaging the worm and worm wheel while gravity return to meshed position is damped.

7. Apparatus for detecting stoppages in the flow of bulk materials through a feeder system including a driven feeding device having a rotating part, a batch delivery device fed by said feeding device and a second feeding device which receives material from the batch delivery device, said second feeding device also including a rotating part which apparatus comprises; means driven by the rotating part of the first feeding device to actuate an alarm signal after a predetermined

angular displacement which is greater than the normal angular displacement incident to the feeding of a batch to the batch delivery device, means driven by the rotating part of the second feeding device to actuate a second alarm system after a predetermined angular displacement which is greater than the normal angular displacement incident to the passage of a batch of bulk material, and means operated by said delivery device upon the delivery of a batch to reset simultaneously both of the means driven by the rotating parts so as to prevent actuation of either alarm signal in normal operation.

8. Apparatus as set out in claim 7 which further comprises means to render the second alarm device inoperative upon actuation of said first alarm device.

9. Apparatus for detecting stoppages in the flow of bulk materials through a feeder system including a driven feeding device, a batch delivery device receiving material from said feeding device, and a second feeding device which receives material from said batch delivery device, said second device including a rotating part, which comprises; means driven by the rotating part of the second feeding device to actuate an alarm signal after a predetermined angular displacement which is greater than the normal angular displacement incident to passage of a batch of bulk material, and means operated by said delivery device upon the delivery of a batch to reset the rotating part of said second feeding means and thus in normal operation prevent the actuation of the alarm.

10. Apparatus for detecting stoppages in the flow of bulk material through a feeder system which includes a bulk material measuring device and a driven feeding device, that comprises an alarm device, an electric circuit controlling operation of said alarm device, a switch in said circuit, means driven by the feeding device to close said switch after a predetermined displacement greater than the normal displacement incident to supplying a predetermined quantity of bulk material, and means operated by said material measuring device upon the delivery of a predetermined quantity of bulk material to reset the means driven by the feeding device and thus in normal operation prevent the closing of the switch in the alarm circuit.

ARTHUR J. STOCK.
NATHANIEL BREWER.
